UNITED STATES PATENT OFFICE.

FRANCIS J. COLE, OF SCHENECTADY, NEW YORK.

LOCOMOTIVE DRIVING-BOX.

1,218,375.

Specification of Letters Patent.

Patented Mar. 6, 1917.

Application filed March 6, 1916. Serial No. 82,290.

To all whom it may concern:

Be it known that I, FRANCIS J. COLE, of Schenectady, in the county of Schenectady and State of New York, have invented a certain new and useful Improvement in Locomotive Driving-Boxes, of which improvement the following is a specification.

The driving box construction which is ordinarily applied in locomotives consists of an integral body of cast iron or steel, in which a semi-circularly bored bearing is firmly fixed, usually by being forced in place by hydraulic pressure. The vertical bearing pressure resultant upon the weight of the supported load is ordinarily limited to about 200 pounds per inch of projected area, and, of course, acts in a vertical direction. The horizontal forces resultant upon the pressure of the steam upon the piston, acting through the leverage of the crank pins, driving wheels, and axles, are considerably greater than that of gravity. Upon a combination of these forces, there is produced a resultant of about 30 degrees from the horizontal, but the intensity of the pressure due to the horizontal forces is much greater than that of the portion of the weight of the locomotive which is supported on the journal. The natural result of this condition is to wear the boxes horizontally very fast, thereby occasioning a pound or knock, which indicates that the bearing does not fit closely on the journal, in a horizontal plane. When this occurs, it is usually necessary to remove the wheels from the locomotive and re bore the brasses, cutting away much of the top bearing.

The object of my invention is to provide a construction in which the bearing surface which opposes the horizontal forces may be materially increased, as to the extent of being more than doubled, and means provided for taking up the wear, and in which the bearings can be readily removed for renewal, without taking the wheels from under the locomotive.

The improvement claimed is hereinafter fully set forth.

In the accompanying drawings: Figure 1 is a view, in perspective, of a locomotive pedestal, fitted with a driving box illustrating an embodiment of my invention; Fig. 2, a plan or top view of the driving box; Fig. 3, a view, partly in outer end elevation and partly in vertical transverse section on the line $\alpha\alpha$ of Fig. 4; Fig. 4, a view, partly

in side elevation and partly in vertical longitudinal section on the line $y\gamma$ of Figs. 3 and 6; Fig. 5, a plan or top view of one of the side sections of the driving box; Fig. 6, a view, partly in front elevation and partly in vertical transverse section on the line $x\alpha$ of Fig. 4, of the top section of the driving box; Fig. 7, a front view of one of the side sections of the driving box; Fig. 8, a plan view of an adjusting key; Fig. 9, a side view of the same; Fig. 10, a view, partly in plan and partly in horizontal transverse section on the line $z\alpha$ of Fig. 12, of a driving box, illustrating a structural modification; Fig. 11, a view, partly in outer end elevation and partly in vertical transverse section on the line $w\alpha$ of Fig. 12, of the same; Fig. 12, a view, partly in side elevation and partly in vertical longitudinal section on the line $v\alpha$ of Figs. 10 and 11, showing also a spring saddle and a transverse section through the upper rail of a locomotive frame member; Figs. 13, 14 and 15, plan, side, and end views, respectively, of the top journal bearing section; Figs. 16, 17 and 18, inner side, top, and end views, respectively, of one of the side journal bearing sections; Fig. 19, a plan or top view of a driving box, illustrating another structural modification; Fig. 20, a view, partly in outer end elevation and partly in vertical transverse section on the line $t\alpha$ of Fig. 21, of the same; Fig. 21, a view, partly in side elevation and partly in vertical longitudinal section on the line $s\alpha$ of Fig. 20; Fig. 22, a horizontal section, on the line $p\alpha$ of Fig. 20; and, Figs. 23, 24 and 25, face, end, and side views, respectively, of an adjusting plate.

Referring first to Figs. 1 to 9 inclusive, my invention is illustrated as applied in a driving box which is fitted, with the capacity of relative vertical movement, between a shoe, 1, and a wedge, 2, which is operated by a screw, 2^a, in a locomotive frame pedestal, the jaws, 3, 3, of which extend from an upper frame rail, 4, to a lower frame rail, 5. The portion of the weight of the locomotive which is supported by the journal, 6, of the driving axle on which the driving box rests, is applied to the top of the driving box through a spring saddle, 7, which straddles the upper frame rail, and supports a driving spring, which is not shown, 110 in the usual manner.

The driving box proper comprises three

independent and relatively movable sections, to wit: a horizontal top section, 8, and two vertical side sections, 8^a, 8^b, the outer sides of which fit against the shoe and wedge, respectively, of the pedestal, and between the top portions of which the top section, 8, is interposed. Recesses, 8^c, are formed in the top section, to receive the legs of the spring saddle, 7. A lubricant cellar, 9, is located between the lower portions of the side sections, and is connected detachably thereto by pins, 9^a. Liners, 10, of thin sheet metal, are fitted between the upper portions of the side section and the top section, and are held against displacement by an upward extension, 8^b, of the top plate, at one end of the box, and by a detachable plate, 10^a, at the opposite end, said plate being secured to the side sections by stud bolts, 10^b, and nuts, 10^c. Liners, 11, are fitted between the sides of the lubricant cellar and the side sections of the driving box, and are held in position, when the cellar is removed for inspection or repacking, by bolts, 11^a.

The journal bearing or "brass" of the driving box is, similarly thereto, formed in three sections, these being a top section, 12, which is fitted in the top section, 8, of the box, and is held longitudinally in position therein by downward projections thereon, and two side sections, 12^a, 12^b, each of which extends below the center of the journal, and is fitted in a dovetail recess, 8^c, in one of the side plates, into which recess it may either be forced into place, or be held therein by a wedge, 13, and adjusting bolt, 13^a. By reference to Fig. 3, it will be seen that the journal bearing sections are disposed symmetrically about the axial line of the journal, and are relatively adjustable, both horizontally and vertically, the top section, which sustains the weight imposed on the box, being a "floating" or vertically movable one, and the side sections being also vertically movable, as well as laterally adjustable, as wear takes place; that the bearing surface on the journal is materially increased as compared with the ordinary construction, as it extends over more than 180 degrees of the circumference of the journal; and that such increase presents an area of resistance to horizontal forces which is not provided in such construction.

When, by reason of knocking, pounding, or slackness of the bearing on the journal, it becomes necessary or desirable to take up wear or lost motion, the liners, 10 and 11, are removed, and the side sections of the driving box, with their bearing sections, are closed together by adjustment of the pedestal wedge, 2, by its operating screw, 2^a.

It is also practicable to utilize one of the forms of automatic spring adjusting wedges which are known in railroad practice, by

which the slack can be automatically taken up when the liners are withdrawn.

Figs. 10 to 18 inclusive illustrate a structural modification, in which the driving box, 8^a, is an integral structure, but independent top and side journal bearing sections, 12, 12^a, 12^b, are provided, as in the instance first described. As an additional feature of improvement, which is similarly applicable in connection with the other embodiments of my invention which are herein set forth, lips, 12^b, are formed on the journal bearing sections, each of which engages a corresponding recess in an adjoining bearing section, the lips and recesses being disposed so that, if grease lubricant is used, the journal bearings will become filled with it, and it will be retained for lubrication and not squeezed out at the ends. As shown in Figs. 11 and 12, a liner, 14, is interposed between the top of the driving box and the top journal bearing, 12, and openings, 8^d, are formed in the top of the box, through which the legs of the spring saddle, 7, extend, and bear upon the liner, 14, through on which they transmit the spring supported weight to the top journal bearing section, 12.

In the operation of the modified construction last described, the pedestal wedge, 2, performs only its ordinary function, *i.e.*, that of taking up lost motion between the sides of the driving box and the pedestal shoe and wedge, and wear of the side sections of the journal bearing is taken up by the insertion of shims or liners, between the backs of the sections and the adjoining sides of the driving box. For this purpose, the wedges, 13, by which the side journal bearing sections are held in position in the box, are removed, the shims inserted behind the journal box sections and the wedges replaced.

In the structural modification illustrated in Figs. 19 to 25 inclusive, the driving box, 8^a, is, as in the instance last above described, an integral casting, in which independent top and side journal bearing sections, 12, 12^a, 12^b, are fitted, with the capacity of independent adjustment. Wear of the side journal bearing sections may be taken up, as required, by a longitudinally tapered adjusting plate, 15, which is fitted between a corresponding longitudinally inclined outer side of one of the side journal bearing sections and the adjacent side portion of the driving box, and may be moved inwardly, in a horizontal plane, to bring the side bearing sections into contact with the journal, by adjusting screws, 15^a. It will be obvious that, if desired, an adjusting plate may be fitted behind each of the side journal bearing sections.

My invention, which is readily applicable in connection with locomotive frame and spring arrangement constructions of the

present standard types, attains the substantial advantages of providing, by a material and substantial increase of journal bearing surface, means for effectively resisting the 5 horizontal forces which are exerted on the driving boxes in the operation of locomotives and of taking up wear as it occurs in service, and the construction is such that the journal bearings can be removed with convenience and promptness, when renewals 10 are required, without necessitating the delay and cost of taking the wheels from under the locomotive.

I claim as my invention and desire to secure by Letters Patent:

1. The combination, in a locomotive engine, of a frame pedestal; a driving box fitted with the capacity of relative vertical movement therein; a plurality of journal bearing sections disposed in the driving box; means for transmitting weight to the top journal bearing section; and means for effecting independent adjustment of the journal bearing sections relatively to a common 25 axial line.

2. The combination, in a locomotive engine, of a frame pedestal; a driving box fitted with the capacity of relative vertical movement therein; a top journal bearing 30 section and two independent side journal bearing sections, the top section being vertically movable relatively to the side sections; means for transmitting weight to the top journal bearing section; and means for effecting horizontal adjustment of the side 35 sections relatively to a common axial line.

3. The combination, in a locomotive engine, of a frame pedestal; a driving box fitted with the capacity of relative vertical 40 movement therein and comprising a top section and two independent side sections; journal bearing sections, each fitted in one of the driving box sections; means for transmitting weight to the top journal bearing 45 section; and means for effecting independent adjustment of the journal bearing sections relatively to a common axial line.

4. The combination, in a locomotive engine, of a frame pedestal; a driving box 50 fitted with the capacity of relative vertical movement therein and comprising a top section and two independent side sections; journal bearing sections, each fitted in one of the driving box sections; means for transmitting weight to the top journal bearing 55 section; and an adjustable pedestal wedge fitted between one of the side sections and the adjacent pedestal jaw.

5. The combination, in a locomotive engine, of a frame pedestal; a driving box 60 fitted therein and comprising a top section and two independent side sections; journal

bearing sections, each fitted in one of the driving box sections; vertical liners interposed between the top driving box section 65 and the side sections; and an adjustable pedestal wedge fitted between one of the side sections and the adjacent pedestal jaw.

6. The combination, in a locomotive engine, of a frame pedestal; a driving box 70 fitted therein; a top journal bearing section and two independent side journal bearing sections disposed in the driving box; and a spring saddle through which weight is imposed upon the top journal bearing section 75 independently of the side sections.

7. The combination, in a locomotive engine, of a frame pedestal; a driving box fitted therein and having openings in its top for the reception of spring saddle legs; 80 a top journal bearing section and two independent side journal bearing sections disposed in the driving box; a spring saddle passing through the top openings of the driving box and resting on the top journal 85 bearing section; and means for adjusting the side journal bearing sections; relatively to a common axial line.

8. The combination, in a locomotive engine, of a frame pedestal; a driving box 90 fitted therein; a top journal bearing section and two independent side journal bearing sections fitted in the driving box, the top section being vertically movable relatively to the side sections; means for imposing 95 weight upon the top journal bearing section independently of the side journal bearing sections; and means for adjusting the side journal bearing sections relatively to a common axial line. 100

9. The combination, in a locomotive engine, of a frame pedestal; a driving box fitted therein, a top journal bearing section, and two independent side journal bearing sections fitted in the driving box, the top 105 section being vertically movable relatively to the side sections; and an adjusting wedge which is inclined in a horizontal plane and is interposed between one of the side journal bearing sections and the driving box. 110

10. The combination, in a locomotive engine, of a frame pedestal; a sectional driving box fitted therein; a plurality of journal bearing sections, each fitted in one of the sections of the driving box; removable 115 adjustment liners, interposed between the sections of the driving box; and an adjustable pedestal wedge, fitted between one of the sections of the driving box and the adjacent pedestal jaw.

FRANCIS J. COLE.
